(57) **CLAIM**

The ornamental design for a protective face shield frame, as shown and described.

DESCRIPTION

FIG. 1 is a perspective view of a protective face shield frame showing our new design;

FIG. 2 is a front elevational view thereof;

FIG. 3 is a rear elevational view thereof;

FIG. 4 is a side elevational view thereof, the opposite side being a mirror image;

FIG. 5 is a top plan view thereof; and,

FIG. 6 is a bottom plan view thereof.

The portions shown in broken lines are included for illustrative purposes only and form no part of the claimed design.
